(21) Appl. No.: **29/260,100**

The ornamental design for a quick release lever for a bicycle hub, as shown and described.

(22) Filed: **May 19, 2006**

DESCRIPTION

(30) **Foreign Application Priority Data**

FIG. 1 is a perspective view of a quick release lever for a bicycle hub in accordance with my new design;

Dec. 16, 2005 (EM) 000450424-0001/0008

FIG. 2 is a first side view of the quick release lever for a bicycle in accordance with my new design;

(51) **LOC (8) Cl.** **12-11**

FIG. 3 is a second side view of the quick release lever for a bicycle in accordance with my new design;

(52) **U.S. Cl.** **D12/114**

FIG. 4 is an outside elevational view of the quick release lever for a bicycle in accordance with my new design;

(58) **Field of Classification Search** D12/111,

FIG. 5 is an inside elevational view of the quick release lever for a bicycle in accordance with my new design;

D12/114, 122-124, 207, 213; 301/124.2,
301/111.01, 110.5, 111.06; 403/322.4, 374.5,
403/DIG. 4; 280/278, 287; 70/233

FIG. 6 is a first end elevational view of the quick release lever for a bicycle in accordance with my new design; and,

See application file for complete search history.

FIG. 7 is a second end elevational view of the quick release lever for a bicycle in accordance with my new design.
